TELETYPEWRITER SYSTEM

James F. Beattie, Norwood, N. J., and Walter R. Roycroft, Ozone Park, N. Y., assignors to Western Electric Company, Incorporated, New York, N. Y., a corporation of New York

Application September 9, 1936, Serial No. 99,940

13 Claims. (Cl. 178—23)

This invention relates to teletypewriter systems and, more particularly, to systems which include a teletypewriter having contacts for performing various functions.

It is an object of this invention to mount contacts, for performing various functions, in a teletypewriter to be operated by the teletypewriter mechanism in response to the transmission and reception of any or all upper case characters without hindering the printing functions of these characters.

It is also an object of this invention to open and close, by means of a central teletypewriter, telegraph lines leading from a teletypewriter office to other teletypewriter stations.

It is a further object of this invention to provide a central teletypewriter office with an improved switching device for switching various circuits.

It is an additional object of this invention to enable a subscriber at a teletypewriter station to connect his teletypewriter through a teletypewriter central office to another teletypewriter station without the assistance of an operator at the central office thereby effecting a saving in operating time.

It is a further object of the invention to enable subscribers having their lines connected together at a central office to disconnect the lines at the central office without the assistance of an operator at the central office thereby effecting a further saving in operating time.

These and other objects of the invention are attained by means of a plurality of contact assemblies mounted in a teletypewriter at various predetermined positions. The contacts are adapted to be operated by the teletypewriter mechanism in response to certain preassigned teletypewriter signals which may, if desired, be sent from other teletypewriter stations. In the preferred embodiment of the invention, the operation of the contacts serves to operate relays which operate and lock-up to perform any desired functions, such as switching telegraph circuits. Also, in the preferred embodiment of the invention, the operation of a particular contact unlocks the switching relays and causes them to deenergize thereby restoring the system to its normal condition. If desired, these relays may be designed to perform a variety of functions, such as switching on and off a teletypewriter motor at an outlying teletypewriter station.

Most of the contact assemblies are adjustably attached to a pivotally mounted plate, located in the central teletypewriter, and are designed to

be operated by the pull bars. This pivoted plate has an effective position and an ineffective position. Biasing means normally tilt the pivoted plate in its ineffective position so that the contacts are elevated beyond the reach of the pull bars. Control means are provided for tilting the pivoted plate into its effective position for lowering the contacts into the reach of the pull bars. The plate is locked in its effective position by means provided for that purpose. A few of the contact assemblies are mounted in other places in the teletypewriter and are designed to be operated by certain mechanisms in the teletypewriter.

These and other features of the invention will now be described in detail with reference to the drawings in which:

Fig. 1 represents a teletypewriter central office and shows a schematic diagram in perspective of a teletypewriter having its platen assembly in the lower case position and provided with special contacts and circuit connections leading to the switching relays;

Fig. 2 shows the switching relays at the central office and the other teletypewriter stations to which the teletypewriter central office shown in Fig. 1 is connected;

Fig. 3 illustrates the manner in which the contact mounting plate is locked in its effective position;

Fig. 4 shows the contact mounting plate in its unlatched, or ineffective, position; and

Fig. 5 illustrates the means for enabling the contact assemblies to be adjustably mounted on the contact plate.

The teletypewriter T, shown in Fig. 1, is similar to the teletypewriter disclosed in Patent 1,745,633 granted February 4, 1930 to S. Morton et al. The disclosure of this Morton et al. patent is incorporated herein by reference as a part of this specification. However, the invention is not limited to this type of teletypewriter nor is it limited to the specific structure shown in the drawings which is a preferred embodiment of the invention and is shown and described in order to illustrate and explain the features and principles of operation of the invention.

For purposes of illustration, teletypewriter T is shown to be located at a teletypewriter central office although it may be located at an ordinary teletypewriter station, if desired. Connected to this central office by telegraph lines L₁ to L₆, inclusive, are the subscribers' teletypewriter stations S₁ to S₆, inclusive, each of which is provided with a teletypewriter T₁ to T₆, inclusive, and a teletypewriter motor M₁ to M₆, inclusive.

Each of the motors M_1 to M_6 , inclusive, is operated by an individual power supply source B_1 to B_6 , respectively. At stations S_1 , S_2 , S_3 , and S_5 the energizing circuits leading from the respective local power supply sources to the motors are opened and closed by manually operable switches A_1 , A_2 , A_3 , and A_5 , respectively, controlled by the local attendant at each station.

The energizing circuit of the motor M_4 is normally open at the armature and contact A_4 of the normally unoperated relay 43 . This energizing circuit is adapted to be opened and closed by any control method that may be desired, such as the method described in Patent 1,913,431 granted June 13, 1933 to W. Daum. The disclosure of this Daum patent is incorporated herein by reference as a part of this specification. The energizing circuit of motor M_6 is normally open at contact A_6 of relay R_6 located at the central office. It is to be understood that these different motor control circuits may be varied as desired to meet the particular requirements of a given system and that they are shown here for the purpose of illustrating the wide extent to which the invention may be applied. It should also be understood that the invention is capable of use with any other type of line circuits, such as duplex circuits.

The teletypewriter T at the central office has a motor M which is operated by a power supply source B over an energizing circuit closed by a manually operable switch lever A . Motor M operates teletypewriter T by means of gears G_1 and G_2 which alternately raise and lower the reciprocating printing bail 19 to actuate the pull bars selected by the code bars 80 operated by the selecting mechanism 18 , as is described in the Morton et al. patent.

Just above the code bars 80 is a base plate 81 which is attached to the frame 95 of the teletypewriter T by any convenient means, such as screws 82 . Pivotally mounted on base plate 81 by pivot 85 is a contact plate 83 . This pivotal connection provides contact plate 83 with two positions, one an ineffective position and the other an effective position. Contact plate 83 is normally held in its ineffective position by means of a retractile spring 86 as is shown in Fig. 4.

Contact plate 83 is placed in its effective position in response to the reception by relay R of a preassigned teletypewriter code signal. In the preferred embodiment of the invention this signal is a so-called "bell" signal; that is, it is a signal which is designed to effect the ringing of a bell (not shown) in the teletypewriter T . With the type of teletypewriter shown in Fig. 1, a bell signal is what is known as an upper case signal and, accordingly, requires that it be preceded by a "figures" shift signal. Furthermore, if a code signal corresponding to a bell signal should be sent while the platen 27 is in its lower case position, the bell pull bar 87 would not be selected but, instead, another pull bar (not shown) would be selected. This other pull bar is not selected by any upper case signal so its associated type bar (not shown) is blank in the upper case.

The reception of a figures code signal by relay R actuates the selecting mechanism 18 which operates the code bars 80 to select the figures pull bar 47 for enabling its shoulder to be engaged by the printing bail 19 . Bail 19 then elevates pull bar 47 and causes the extension 48 to elevate the left end of bell crank 49 . This causes the right end of bell crank 49 to dip down and

lower catch 79 thereby releasing latch 59 . The release of latch 59 allows spring 51 to pull the platen assembly 52 forward. In moving forward, the platen assembly 52 pulls lever 28 forward sufficiently to remove slot 75 from the path of travel of extension 29 of the so-called "blank" pull bar 14 and, at the same time, closes a contact C_7 for a purpose to be explained hereinafter.

Now, when a bell code signal is received by relay R , selecting mechanism 18 will operate code bars 80 to select the bell pull bar 87 . Bail 19 then engages with the shoulder of the bell pull bar 87 and elevates bar 87 with the result that the upper end of bar 87 pushes the left end of lever 88 upward. Lever 88 is pivotally mounted at 89 (Fig. 4) so that, when its right end goes up, its left end comes down and carries with it link 90 thereby overcoming the tension of spring 86 by pulling down the right edge of the contact plate 83 . This enables latch 91 to engage with catch 92 on contact plate 83 . Retractile spring 94 pulls latch 91 to the left for holding contact plate 83 in its effective position.

Contact plate 83 remains in its effective position until a particular preassigned teletypewriter code signal is received by relay R . In a preferred embodiment of the invention, this particular code signal is what is known as the "letters" shift signal. When this letters shift signal is received by relay R , it effects the selection of the letters pull bar 53 by the code bars 80 . Bail 19 then elevates the letters pull bar 53 so that the top end of bar 53 hits against lever 93 and causes it to turn counterclockwise around its pivot thereby overcoming the pull exerted by spring 94 and tripping latch 91 . The release of latch 91 allows retractile spring 86 to pull the contact plate 83 back to its normal, or ineffective, position.

Adjustably mounted along the contact plate 83 in the manner shown in Fig. 5 are the assemblies for contacts C_1 , C_2 , C_3 , C_5 , and C_6 . Although these contact assemblies have been shown to be adjustably mounted, it is to be understood that this is merely one form of the invention and that the contact assemblies may be fixedly located by being drilled and tapped onto the contact plate 83 . All of these contacts are normally open except contact C which is normally closed. Contacts C_1 , C_2 , C_3 , C_5 , and C_6 are each designed to be momentarily operated in response to only upper case selections of pull bars 17 , 12 , 13 , 15 and 16 , respectively, and are then effective to perform their intended functions only when their operating signals are preceded by a preassigned code signal which, in the preferred embodiment of the invention, is a so-called "bell" signal. Thus, the pull bars 17 , 12 , 13 , 15 and 16 may be used for performing their normal lower and upper case printing functions as well as for operating contacts C_1 , C_2 , C_3 , C_5 , and C_6 to perform various functions, such as switching telegraph lines, as will be described hereinafter.

In addition to these switching contacts, the switching mechanism also includes the normally open contact C_7 which is operated by the platen assembly in the manner described above. The switching mechanism further includes the normally open contacts C_1 and C_4 which are designed to be operated by portions of the teletypewriter mechanism only in response to the reception by the receiving relay R of certain upper case teletypewriter code signals. The manner of operating contacts C_1 and C_4 will be described here-

inafter in connection with the description of the operation of the system as a whole.

In the operation of the system, let it first be assumed that the subscriber at station S₁ wishes to connect himself through the central office to the subscriber at station S₃. The subscriber at station S₁ normally has his switch A₁ closed during business hours so that his motor M₁ is energized by his local power supply source B₁. Accordingly, the subscriber, by means of his teletypewriter T₁, first transmits a figures shift signal out over line L₁, conductor 20, line L₂, through station S₂, line L₂, conductor 21, through the normally closed contacts of relay R₂, conductor 22, through the normally closed contacts of relay R₁, conductor 23, sending contacts 26, conductor 10, receiving relay R, conductor 8, outer left armature of the normally unoperated relay R₄, and then to grounded battery 24.

The figures shift signal transmitted over this path energizes the receiving relay R which operates the selecting mechanism 18 to select the figures pull bar 47 which is then elevated by the printing bail 19. In rising, pull bar 47 causes its extension 48 to elevate the left end of bell crank 49. This causes the right end of bell crank 49 to dip down and lower catch 79 thereby releasing latch 50. The release of latch 50 allows spring 51 to pull the platen assembly 52 forward. As was stated above, the forward movement of the platen assembly 52 pulls lever 28 forward sufficiently to remove slot 75 from the path of travel of extension 29 of the so-called "blank" pull bar 14. At the same time, the forward movement of the platen assembly 52 closes contact C₇ for a purpose to be explained herein-after.

The subscriber at station S₁ now transmits a preassigned code combination of significant current variations which, in this preferred embodiment of the invention, is known as a "blank" signal. Upon being received at the central office, this particular upper case code signal causes the selecting mechanism 18 to select the blank pull bar 14. Accordingly, the printing bail 19 elevates the blank pull bar 14 with the result that extension 29 of pull bar 14 engages with the left end of lever 28 and raises it up. This elevates the left end of lever 30 and, consequently, lowers the right end of lever 30 thereby allowing spring 31 to pull down the left end of lever 32. As a result, the right end of lever 32 is raised and allows the spring contact C₄ to close. This closing is only momentary because pull bar 14 is soon lowered by bail 19, and spring 77 then pulls lever 28 back into the position shown in the drawing.

It should be noted that contact C₄ can only be closed by this upper case blank signal because, when the platen assembly 52 is in its lower case position (as is shown in Fig. 1), slot 75 in lever 28 is then positioned over extension 29 of the blank pull bar 14. Elevation of pull bar 14 would then be futile to cause the closing of contact C₄ because extension 29 would pass through slot 75 and would thus be unable to tilt lever 28.

The closing of contact C₄ momentarily closes the energizing circuit of relay R₄ from grounded battery 33, through the winding of relay R₄, conductor 4, contact C₄, conductor 9, conductor 36, and then to ground 37. As a result, relay R₄ becomes energized and operates both its armatures. Before contact C₄ opens, relay R₄ locks-up over a path leading from grounded battery 33, through

the winding of relay R₄, inner left armature, conductor 34, conductor 7, through the normally closed contact C, conductor 35, conductor 36, and then to ground 37. At the same time, the communication circuit is switched from grounded battery 24 to the joining conductor 38 and then to conductor 39, out over line L₆ to station S₆, over line L₆, conductor 40, line L₃, and then to station S₃.

Since the subscriber at station S₃ normally has his switch A₂ closed during business hours, his motor M₃ will be energized at this time by his local power supply source B₃. Accordingly, the system is now in condition for communication to take place between the subscriber at station S₁ and the subscriber at station S₃. Significant current variations transmitted by the teletypewriter T₁ will travel over line L₁, conductor 20, line L₂, through station S₂, line L₂, conductor 21, conductor 22, conductor 23, sending contacts 26, conductor 10, receiving relay R, conductor 8, conductor 38, conductor 39, line L₆, through station S₆, line L₆, conductor 40, line L₃, and then to station S₃.

When, during the course of communication, the subscriber at station S₁ wishes to effect a lower case selection, he transmits the so-called "letters" shift code signal for causing the selecting mechanism 18 of teletypewriter T to operate the code bars 33 to select pull bar 53. Upon being elevated by the printing bail 19, pull bar 53 elevates its extension 54 which correspondingly elevates the left end of lever 55 thereby depressing the right end of lever 55. When the right end of lever 55 is depressed, it causes the left end of bell crank 56 to be correspondingly depressed, thereby causing the top end of bell crank 56 to move backward to the rear of the teletypewriter T. This acts as a lever to pull back the platen assembly 52. In traveling to the rear of the teletypewriter T, the platen assembly 52 causes latch 50 to also move to the rear of the teletypewriter T with the result that latch 50 will engage with the catch 79 in the right end of bell crank lever 49. This serves to hold the platen assembly 52 in its rearward position and prevents spring 51 from pulling it forward. Thus, the platen assembly 52 is latched in its lower case position, as is shown in Fig. 1, where it remains until a figures shift signal is received by relay R.

Since both stations S₄ and S₅ are disconnected from the communication circuit at the armatures of relays R₁ and R₂, respectively, neither teletypewriter T₄ nor teletypewriter T₅ will record the signals sent from teletypewriter T₁ at this time. Teletypewriter T₆ will also not record these signals due to the fact that the energizing circuit for its motor M₆ is open at contact A₆ of relay R₆. However, with the system in the condition shown in the drawings, teletypewriter T₂ will follow the signals transmitted by teletypewriter T₁ because the energizing circuit for its motor M₂ is closed at switch A₂. If the subscriber at station S₂ finds that the message being transmitted from station S₁ to station S₃ is of no interest to him, he can open switch A₂ thereby shutting down his motor M₂ with the result that his teletypewriter T₂ will not now record the signals being transmitted.

Thus, the subscriber at station S₁, which may be located at a remote point, has connected himself through the central office to the distant subscriber's station S₃ without any assistance from an operator at the central office. In other words,

the subscriber at station S_1 has switched both his and the other subscriber's lines 8 and 39 from their terminations at batteries 24 and 25 , respectively, to the joining conductor 38 thereby switching the line conductors 8 and 39 together. Consequently, a considerable saving in operating time is effected since the subscriber at station S_1 simply transmits the upper case code combination assigned to select pull bar 14 which closes contact C_4 to operate relay R_4 which immediately switches the two lines 8 and 39 together without any act by an operator at the central office. This saving in operating time is of importance in certain types of business where time is of the essence and promptness in putting calls through is essential.

When the subscribers at stations S_1 and S_3 have finished communicating with each other, either one of them may effect a disconnection of their lines 8 and 39 at the central office by transmitting, from either station S_1 or station S_3 , a figures shift signal followed by a preassigned telegraphic signal, which in this preferred embodiment of the invention, is a bell signal. This bell signal is received by the receiving relay R at the central office which accordingly actuates the selecting mechanism 18 to operate the code bars 80 to select the bell pull bar 87 . The resulting elevation of bar 87 by the reciprocating bail 19 causes lever 28 to be tilted thereby pulling down the contact plate 83 which is then latched in its effective position by latch 91 as was described above.

Then, either of the subscribers transmits another preassigned code signal which causes code bars 80 to select pull bar 17 . Bail 19 then elevates pull bar 17 which momentarily opens the normally closed contact C thereby opening the locking-up circuit of relay R_4 . Consequently, relay R_4 releases its armatures and switches the line conductors 8 and 39 from the joining conductor 38 to batteries 24 and 25 , respectively, thereby disconnecting stations S_1 and S_3 from each other and restoring the circuits to their normal condition. If desired, the subscriber at station S_2 may also effect this disconnection. Since this disconnection is accomplished by any of the connected subscribers without the assistance of an operator at the central office, a further saving in operating time is effected.

The nature of the business of the subscriber at station S_1 may be such that it would be desirable for him to send a message to both the subscriber at station S_3 and the subscriber at station S_6 (which may, for example, be an outlying station near the central office) and have the message recorded practically simultaneously by the teletypewriters T_3 and T_6 . To accomplish this conference connection, it is first necessary to start the teletypewriter motor M_6 at station S_6 by energizing relay R_6 . Accordingly, the subscriber at station S_1 transmits a figures shift signal for selecting the figures pull bar 47 to effect the release of latch 50 which then allows the platen assembly 52 to be pulled forward by spring 51 . In moving forward, the platen assembly 52 carries latch 50 forward along the top edge of bell crank lever 49 thereby forcing down the right end of bell crank lever 49 to close contact C_7 . Since latch 50 now engages with the catch 79 in the right end of bell crank lever 49 , contact C_7 will remain closed during the time that the platen assembly 52 remains in its upper case position.

The subscriber at station S_1 next transmits a bell signal over line L_1 , conductor 20 , line L_2 ,

through station S_2 , line L_2 , conductor 21 , conductor 22 , conductor 23 , sending contacts 26 , conductor 10 , receiving relay R , conductor 8 , and then to grounded battery 24 . This effects the selection of the bell pull bar 87 which causes the contact plate 83 to be latched in its effective position in the manner described above. The subscriber at station S_1 now transmits a pre-assigned combination of code impulses over the circuit traced above. This code combination causes the selecting mechanism 18 of teletypewriter T to select pull bar 16 which is then operated by the printing bail 19 to close contact C_6 momentarily. A path for energizing relay R_6 is now closed from grounded battery 41 , through the winding of relay R_6 , conductor 6 , through contact C_6 , conductor 76 , conductor 9 , conductor 36 , and then to ground 37 .

As a result, relay R_6 operates its armatures and locks-up through a path from battery 41 , through the winding of relay R_6 , operated left armature, conductor 34 , conductor 7 , through the normally closed contact C , conductor 35 , conductor 36 , and then to ground 37 . At the same time, the right armature of relay R_6 is operated and closes a path from power supply source B_6 at station S_6 , over line conductor 45 , operated armature and contact A_6 of relay R_6 , line conductor 46 , motor M_6 , and then back to power supply source B_6 thereby energizing motor M_6 and starting it into operation. The subscriber at station S_1 then transmits the code signal for selecting pull bar 14 in the teletypewriter T at the central office. When bail 19 elevates pull bar 14 , contact C_4 will be momentarily closed and relay R_4 will operate its armatures and lock-up in the manner described above.

Messages now sent from station S_1 will pass through station S_2 , through the central office, and then through stations S_6 and S_3 . The messages will thus be recorded practically simultaneously on both the teletypewriters T_3 and T_6 . They will also be recorded on the teletypewriter T_2 at station S_2 provided the subscriber at this station has his switch A_2 closed. The subscriber at station S_2 can transmit messages to any of the connected stations and these messages will be practically simultaneously recorded by the teletypewriters T_1 , T_2 , and T_6 . Likewise, the subscriber at station S_6 can also send messages which will be recorded on all of the connected teletypewriters.

At the close of communication, if the platen assembly 52 happens to be in its upper case position, any of the subscribers at stations S_1 , S_2 , S_3 , or S_6 may disconnect the conference connection by transmitting a bell signal to place plate 83 in its effective position and by then transmitting the preassigned code signal for selecting pull bar 17 , which will momentarily open the normally closed contact C as was described above. However, if the platen assembly 52 happens to be in its lower case position, then the bell signal must be preceded by a figures signal before contact plate 83 can be placed in its effective position. The opening of contact C will open the locking-up circuits of both relays R_4 and R_6 and will cause them to release their armatures. This switches the communication circuit from conductors 8 and 39 to grounded batteries 24 and 25 as was described above. At the same time, the energizing circuit of motor M_6 is opened at contact A_6 of relay R_6 and, consequently, motor M_6 stops running. The circuits are thus restored to their normal condition.

In the event that the subscriber at station S_1 wishes to communicate with the subscriber at station S_4 (which may, for example, be an out-lying station near the central office), he will transmit the figures shift signal to cause the platen 27 to be shifted to its upper case position. The subscriber will then transmit a preassigned upper case code signal which, upon being received by the receiving relay R , will effect the selection of pull bar 11 by the selecting mechanism 18 and the code bars 80 . The elevation of pull bar 11 by bail 19 will, by means of ratchet 57 and gear 58 , drive the top of type bar 59 downward in an arcuate path. The projection 84 on bar 59 will then hit lever 60 thereby tilting downward the right end of lever 61 . This drives the top end of lever 61 to the right and allows spring 62 to pull down the right end of lever 63 into latching engagement with the top end of lever 61 . Consequently, the left end of lever 63 , which is normally located immediately beneath the printing bail 19 , as shown in the drawings, is driven upward to close contact C_1 momentarily. It should be noted that contact C_1 can only be closed by an upper case selection of pull bar 11 because, when the platen assembly 52 is in its lower case position, lever 60 is carried to the rear of teletypewriter T a short distance which is sufficient to remove it from the path of travel of projection 84 .

The closure of contact C_1 closes a path from grounded battery 64 , through the winding of relay R_1 , along conductor 1 , through contact C_1 , conductor 65 , conductor 36 , and then to ground 37 . Consequently, relay R_1 operates both its armatures and locks-up through its right armature over a path from grounded battery 64 , winding of relay R_1 , operated right armature and contact of relay R_1 , conductor 34 , conductor 1 , normally closed contact C , conductor 35 , conductor 36 , and then to ground 37 . It is necessary that relay R_1 be designed to lock-up quickly because, when the reciprocating bail 19 comes down, it strikes the left end of lever 63 thereby knocking the right end of lever 63 up out of latching engagement with the top end of lever 61 . This permits contact C_1 to resume its normally open position.

The operation of the two left armatures of relay R_1 opens the normally closed make-before-break left contacts of relay R_1 and closes a path from conductor 22 , over the inner left armature of relay R_1 , conductor 66 , line L_4 , through station S_4 , back over line L_4 , conductor 67 , outer left armature of relay R_1 , conductor 23 , sending contacts 26 , conductor 19 , relay R , conductor 8 , and then to grounded battery 24 . The subscriber at station S_1 now transmits motor start signals, such as those described in the Daum patent mentioned above, which effect the energization of a relay 43 at station S_4 similar to the motor control relay disclosed in the Daum patent. Upon being energized, motor control relay 43 operates its armature to close the contact A_4 thereby closing the energizing circuit of motor M_4 and starting motor M_4 into operation.

Communication may now take place between stations S_1 , S_2 , and S_4 , the signals passing out over line L_1 , conductor 20 , line L_2 , through station S_2 , line L_2 , conductor 21 , conductor 22 , conductor 66 , line L_4 , through station S_4 , line L_4 , conductor 67 , conductor 23 , and then to grounded battery 24 as was described above. These signals will also pass through the receiving relay R . It might be mentioned here that this is the case

with all connections between the various subscribers' stations; that is, receiving relay R follows all the signals sent between these stations thereby making a complete record of all the communication which takes place throughout the system.

At the close of communication, any of the subscribers at the three connected stations S_1 , S_2 , and S_4 may, after first putting the platen assembly 52 into its upper case position in the manner described above, send a bell signal followed by the code signal for selecting pull bar 17 which momentarily opens contact C with the consequent opening of the locking-up circuit of relay R_1 . Relay R_1 now releases its armatures and its make-before-break contacts now open the circuit leading to station S_4 and connect conductor 22 directly to conductor 23 . Incidentally, the motor at station S_4 may be stopped by any of the subscribers in the manner described in the Daum patent. It might be stated here that, in this embodiment of the invention, the central office operator can effect any of the connections and disconnections between any of the subscribers' stations because her sending contacts 26 are always connected in series with the communication circuits. This circuit construction can be modified in accordance with the requirements of different systems.

If the subscriber at station S_1 wishes to send a message to be recorded by the teletypewriters T_3 and T_4 at stations S_3 and S_4 (leaving station S_2 out of consideration for the sake of simplicity) he will, after first causing contact plate 83 to be put in its effective position in the manner described above, send the code signals to select pull bars 11 and 14 for closing contacts C_1 and C_4 . This will operate relays R_1 and R_4 which will lock-up as described above to close the lines leading to stations S_3 and S_4 . Any of the connected subscribers may disconnect this conference connection, after placing contact plate 83 in its effective position, by sending the code signal to select pull bar 17 for opening contact C . This opens the locking-up circuits of both relays R_1 and R_4 thereby restoring the system to its normal condition.

Also, if the subscriber at station S_1 wishes to send a message to be recorded by the teletypewriters at each of the stations S_3 , S_4 , and S_6 (again leaving station S_2 out of consideration for the sake of simplification), he will follow the same procedure as that outlined in the preceding paragraph except that he will, in addition, send the code signal to select pull bar 16 . The operation of pull bar 16 will close contact C_6 and will operate relay R_6 which will lock-up and close the energizing circuit of motor M_6 at station S_6 thereby conditioning station S_6 for the reception and transmission of messages. Any of the connected subscribers, or the central office operator, may disconnect this conference connection in the manner described above.

Likewise, the subscriber at station S_1 may connect himself through the central office to station S_5 by first transmitting the figures shift signal for shifting platen 27 in teletypewriter T to its upper case position. The subscriber at station S_1 then transmits a bell signal (thereby placing contact plate 83 in its effective position) followed by the preassigned code combination for selecting pull bar 12 . The elevation of pull bar 12 by bail 19 momentarily closes contact C_2 thereby closing the energizing path for relay R_2 from grounded battery 68 , through the winding of relay R_2 , con-

ductor 2, contact C₂, conductor 99, conductor 9, conductor 36, and then to ground 37 thereby energizing relay R₂.

Upon being energized relay R₂ operates its armatures and locks-ups from battery 68, through the winding of relay R₂, operated left armature, conductor 34, conductor 1, through the normally closed contact C, conductor 35, conductor 36, and then to ground 37. In operating its two right armatures relay R₂ switches the line circuit from along conductor 21, over the outer right operated armature and make-before-break contact of relay R₂, conductor 69, line L₅, teletypewriter T₅ at station S₅, back over line L₅, conductor 10, inner operated right armature and make-before-break contact of relay R₂, conductor 22, conductor 23, and then through the receiving relay R to grounded battery 24.

If a conference connection is desired, other stations may be connected into the communication circuit in the manner described above. At the close of communication, any of the connected subscribers may disconnect the connection by effecting the operation, or opening, of the normally closed contact C at the central office in the manner described above.

In the event that it is desired to connect some other station into the communication circuit, or to perform any other switching function, the platen 27 is first shifted to its upper case position in the manner described above. After a bell signal has been sent to place the contact plate 83 in its effective position, the preassigned upper case code combination is transmitted for selecting pull bar 13.

The operation of pull bar 13 by bail 19 momentarily closes the switching contact C₃ for enabling relay R₃ to operate over a path traced from grounded battery 71 through the winding of relay R₃, conductor 3, contact C₃, conductor 72, conductor 9, conductor 36, and then to ground 37 thereby energizing relay R₃. Upon being energized, relay R₃ operates its armatures and locks-up over a path from grounded battery 71, through the winding of relay R₃, operated left armature, conductor 34, conductor 1, through the normally closed contact C, conductor 35, conductor 36, and then to ground 37. In operating its right armatures, relay R₃ will perform the desired switching function.

When it is desired to discontinue the switching operation, the contact plate 83 is placed in its effective position in the manner described above, the upper case code signal is sent for causing pull bar 17 to open the normally closed contact C which opens the locking-up circuit of relay R₃ thereby causing relay R₃ to release its armatures thus restoring the system to its normal condition.

If it is desired to perform still other switching functions, they may be effected by first shifting the platen 27 to its upper case position. After sending a bell signal to place contact plate 83 in its effective position, the preassigned upper case code combination for selecting pull bar 15 is then transmitted. The elevation of pull bar 15 momentarily operates the switching contact C₅ for closing a path from grounded battery 73, through the winding of relay R₅, conductor 5, contact C₅, conductor 74, conductor 9, conductor 36, and then to ground 37 thereby energizing relay R₅. Upon operating its armatures, relay R₅ will lock-up over a path leading from grounded battery 73, through the winding of relay R₅, operated left armature, conductor 34, conductor 1,

through the normally closed contact C, conductor 35, conductor 36, and then to ground 37. In operating its right armatures, relay R₅ will perform the desired switching functions.

When it is desired to terminate this switching operation, the contact plate 83 is placed in its effective position in the manner described above and the upper case signal for effecting the opening of the normally closed contact C is transmitted thereby opening the locking-up circuit of relay R₅ which now releases its armatures and restores the system to its normally unoperated condition.

Another switching function may be accomplished by means of contact C₇ which is operated by movement of the platen assembly 52 as was described above. That is, contact C₇ is closed when platen assembly 52 is moved forward to its upper case position and is opened when platen assembly 52 moves back to its lower case position. This opening and closing of contact C₇ opens and closes the path along conductors 42 and 44 and may be utilized for accomplishing any desired function analogous to those described above.

If additional operations, or functions, are desired, more contacts can be mounted upon the contact plate 83 and can be connected into the system in a manner similar to that in which the other contacts are connected.

Whereas the operation of the system has been described principally with reference to connections originating from the dominant station S₁, it is to be understood that the connections described above may be effected and disconnected in a similar manner by the subscriber at the other dominant station S₂. It is to be further understood that other dominant stations may be added according to the particular requirements of an individual system.

For the purpose of illustration, contact C₁ has been shown to be operable by an individual arrangement of the teletypewriter apparatus. If it is desired to have levers 69, 61, and 63 perform some other function, contact C₁ may be mounted on the contact plate 83 above a pull bar the same as contacts C₂, C₃, C₅, and C₆.

The same applies to contact C₄ which has also been shown to be operable by an individual arrangement of the teletypewriter apparatus. If it is desired to have levers 28, 30, and 32 perform some other function, this may readily be accomplished by placing contact C₄ on the contact plate 83 above a pull bar the same as contacts C₂, C₃, C₅ and C₆.

All of the contact assemblies on plate 83 have been shown to be adjustably mounted in order that their positions may be readily varied to meet the requirements of different systems. It is to be understood that this has been done for the purpose of illustration and that they may be fixedly mounted on plate 83 by being drilled and tapped thereto. The preferred method of adjustably mounting the contact assemblies is shown in Fig. 5 in which the contact assembly 96 is shown to be provided with a spring contact C_x and a clamp 97 having a screw 98. To install this contact assembly 96, it is slid onto the contact plate 83 in such a manner that the clamp 97 embraces the contact plate 83 as shown in Fig. 5. The contact assembly 96 is then slid along the contact plate 83 until it is over the top of the proper pull bar. The screw 98 is then tightened so that the contact assembly 96 is held firmly in place on the contact plate 83.

This position of the contact assembly 96 may

be changed by first loosening screw 98, then sliding assembly 96 along contact plate 83 to its new location, and then tightening screw 98. Contact assembly 96 can also be readily removed by simply 5 loosening screw 98 and then sliding assembly 96 off the contact plate 83. Thus, it can be seen that the use of this adjustably mounted contact assembly 96 renders the apparatus more flexible and adaptable to meet different and changing requirements of the system.

It may be stated here that, after contact plate 83 has been latched in its effective position and after the desired switching relays have been operated and have locked-up, then the desired message, or messages, are sent to the connected stations. As soon as a letters code signal appears in the message, pull bar 53 will be selected by code bars 80 and will be operated by the reciprocating bail 19. The elevation of pull bar 53 operates 10 lever 93 which trips latch 91. As was described above, the release of latch 91 permits spring 86 to pull contact plate 83 into its ineffective position. However, this has no effect on the status of the switching relays at this time because all the 15 operated switching relays remain locked-up. This is because the movement of contact plate 83 from its effective position to its ineffective position does not open the normally closed contact C. Contact C remains closed until contact 20 plate 83 is again placed in its effective position and pull bar 17 operated as was described above.

Thus, by means of this invention, the various pull bars of the teletypewriter T at the central office may be used for performing their regular 25 printing functions in response to both upper and lower case selections. The restriction of the switching functions of the pull bars to only those upper case selections which have been preceded by a bell signal facilitates regular communication 30 between the stations during the period that the contact plate 83 is in its ineffective position. This is due to the fact that, if contact plate 83 were not in its ineffective position, every time the pull bars should be operated they would close 35 their contacts to operate the particular switching relays associated therewith.

It is to be understood that this specific application of the invention has been shown and described for purposes of explaining the principles and features of operation of the invention. 40 Many changes may be made in the construction shown without exceeding the scope of the invention. More switching contacts to be operated by the pull bars of the teletypewriter at the central 45 office may be added whenever desired to perform any functions that may be required. Likewise, the circuit connections of the various subscribers' stations may be varied as desired to meet the requirements of any particular communication 50 system.

For example, the teletypewriter at each subscriber's station could be provided with these switching contacts and circuit connections. This would enable a subscriber to perform the various 55 switching operations desired without sacrificing the ordinary upper and lower case printing functions associated with the pull bars of his teletypewriter. Thus, after connecting himself to the desired stations, the subscriber could avail himself completely of the ordinary printing functions 60 of his teletypewriter.

What is claimed is:

1. A teletypewriter having pull bars, selecting mechanism for selecting certain of the pull 65 bars, a bail for elevating those pull bars selected

by the selecting mechanism, a plate pivotally mounted near the pull bars, contacts mounted upon the plate and positioned above the pull bars, said contacts being adapted to be operated by the pull bars when the pull bars are elevated, said pivoted plate having an ineffective position for elevating the contacts beyond the reach of the pull bars and an effective position for lowering the contacts into the reach of the pull bars, biasing means for tilting the pivoted plate into its 10 ineffective position, and control means for tilting the plate into its effective position.

2. A teletypewriter having a plurality of pull bars, selecting mechanism for selecting certain of the pull bars, a bail for elevating those pull 15 bars selected by the selecting mechanism, a plate pivotally mounted near the pull bars, contacts mounted upon the plate and positioned immediately above the pull bars, said contacts being adapted to be operated by the pull bars when the 20 pull bars are elevated, circuits adapted to be opened and closed by the contacts, said pivoted plate having an ineffective position for elevating the contacts beyond the reach of the pull bars and an effective position for lowering the contacts 25 into the reach of the pull bars, biasing means for tilting the pivoted plate into its ineffective position, control means for tilting the plate into its effective position, and locking means for locking the plate in its effective position.

3. A teletypewriter having a plurality of pull bars, selecting mechanism for selecting certain of the pull bars, a bail for elevating those pull 30 bars selected by the selecting mechanism, a plate pivotally mounted in the teletypewriter just above the pull bars, and a plurality of contacts adjustably mounted upon the plate in operative relationship with the pull bars, said contacts being adapted to be operated by the pull bars.

4. A teletypewriter having a plurality of pull 35 bars, a reciprocating bail for elevating the pull bars, a base plate located near the tops of the pull bars, a contact plate pivotally mounted upon the base plate, a plurality of contact assemblies mounted upon the contact plate, each of said contact assemblies having a contact projecting over the edge of the contact plate and adapted to be operated by the pull bars when elevated by the bail, said contact plate having an ineffective position for maintaining the contacts above the upper limit of the path of travel of the pull bars and an effective position for lowering the contacts into the path of travel of the pull bars, and a spring for holding the contact plate in its ineffective position.

5. A teletypewriter having a plurality of pull bars, a reciprocating bail for elevating the pull bars, a base plate located near the tops of the pull bars, a contact plate pivotally mounted upon the base plate, a plurality of contact assemblies 45 mounted upon the contact plate, each of said contact assemblies having a contact projecting over the edge of the contact plate and adapted to be operated by the pull bars when elevated by the bail, said contact plate having an ineffective 50 position for maintaining the contacts above the upper limit of the path of travel of the pull bars and an effective position for lowering the contacts into the path of travel of the pull bars, a spring for holding the contact plate in its ineffective position, a latch for latching the contact plate in its effective position, and a lever for bringing the contact plate into latching engagement with the latch.

6. A teletypewriter having a plurality of pull 75

bars, a reciprocating bail for elevating the pull bars, a base plate located near the tops of the pull bars, a contact plate pivotally mounted upon the base plate, a plurality of contact assemblies 5 mounted upon the contact plate, each of said contact assemblies having a contact projecting over the edge of the contact plate and adapted to be operated by the pull bars when elevated by the bail, said contact plate having an ineffective position for maintaining the contacts above the 10 upper limit of the path of travel of the pull bars and an effective position for lowering the contacts into the path of travel of the pull bars, a spring for holding the contact plate in its ineffective position, a latch for latching the contact plate in its effective position, and a lever for bringing the contact plate into latching engagement with the latch, said lever being adapted to be operated by a preassigned pull bar of the teletypewriter.

7. A teletypewriter having a plurality of pull bars, a reciprocating bail for elevating the pull bars, a base plate located near the tops of the pull bars, a contact plate pivotally mounted upon the 25 base plate, a plurality of contact assemblies mounted upon the contact plate, each of said contact assemblies having a contact projecting over the edge of the contact plate and adapted to be operated by the pull bars when elevated by the 30 bail, said contact plate having an ineffective position for maintaining the contacts above the upper limit of the path of travel of the pull bars and an effective position for lowering the contacts into the path of travel of the pull bars, a 35 spring for holding the contact plate in its ineffective position, a latch for latching the contact plate in its effective position, a first lever for bringing the contact plate into latching engagement with the latch, and a second lever for releasing the latch from its latching engagement 40 with the contact plate.

8. A teletypewriter having a plurality of pull bars, a reciprocating bail for elevating the pull bars, a base plate located near the tops of the 45 pull bars, a contact plate pivotally mounted upon the base plate, a plurality of contact assemblies mounted upon the contact plate, each of said contact assemblies having a contact projecting over the edge of the contact plate and adapted 50 to be operated by the pull bars when elevated by the bail, said contact plate having an ineffective position for maintaining the contacts above the upper limit of the path of travel of the pull bars and an effective position for lowering 55 the contacts into the path of travel of the pull bars, a spring for holding the contact plate in its ineffective position, a latch for latching the contact plate in its effective position, a first lever for bringing the contact plate into latching engagement with the latch, and a second lever for releasing the latch from its latching engagement 60 with the contact plate, said second lever being adapted to be operated by a preassigned pull bar of the teletypewriter.

65 9. A teletypewriter system having a teletypewriter central office having a teletypewriter with a platen, a plurality of subscribers' teletypewriter stations connected to the central office by a plurality of telegraph lines, switching apparatus at 70 the central office for enabling a subscriber at one of the teletypewriter stations to establish a con-

ference connection through the central office with a plurality of the other subscribers' stations, said switching apparatus including a pivotally mounted contact plate, a plurality of switching contacts mounted upon the contact plate, and control means for operating the switching contacts in response to the reception by the teletypewriter at the central office of preassigned teletypewriter signals transmitted over one of the lines by one of the stations.

10 10. A teletypewriter system having in combination a teletypewriter central office having a teletypewriter with a platen, a plurality of telegraph lines, a plurality of subscribers' teletypewriter stations connectable to the central office 15 by the telegraph lines and normally disconnected from each other, and switching apparatus for enabling a subscriber at one of the teletypewriter stations to connect himself through the central office to one of the other teletypewriter 20 stations, said switching apparatus including a pivotally mounted contact plate mounted in the teletypewriter at the central office and a plurality of switching contacts mounted upon the contact plate.

25 11. A teletypewriter system having in combination a teletypewriter central office having a teletypewriter with a platen having an upper case position and a lower case position, shift mechanism for shifting the platen from one of said 30 positions to the other, a plurality of telegraph lines, a plurality of subscribers' teletypewriter stations connectable to the central office by the telegraph lines and normally disconnected from each other, and switching apparatus for enabling 35 a subscriber at one of the teletypewriter stations to connect himself through the central office to one of the other teletypewriter stations, said switching apparatus including a pivotally mounted contact plate mounted in the teletypewriter 40 at the central office and a plurality of switching contacts mounted upon the contact plate, said switching contacts being operable only when the platen is shifted to a preassigned case position.

45 12. A teletypewriter having pull bars, selecting mechanism for selecting certain of the pull bars, a reciprocating bail for elevating those pull bars selected by the selecting mechanism, a contact plate pivotally mounted near the pull bars, a plurality of contacts mounted upon the contact 50 plate and adapted to be operated by the pull bars when the pull bars are elevated, circuits adapted to be opened and closed by the contacts, and an instrumentality for moving the contact plate about its pivot to render the contacts inoperable.

55 13. A teletypewriter having shift mechanism, a plurality of pull bars, selecting mechanism for selecting certain of the pull bars, a bail for elevating those pull bars selected by the selecting mechanism, a contact plate pivotally mounted in 60 the teletypewriter near the pull bars, a plurality of contacts mounted upon the contact plate and adapted to be operated by the pull bars when the pull bars are elevated, a plurality of circuits adapted to be opened and closed by the operation 65 of the contacts, said contacts being normally inoperable, and an instrumentality operable by a preassigned teletypewriter code signal for rendering said contacts operable.
